DESIGN FOR A LUBRICATING UNIT

Billy M. Stephens, Warren, Pa., assignor to Hyvis Oils, Inc., Warren, Pa., a corporation of Delaware

Application October 24, 1935, Serial No. 59,199

Term of patent 7 years

To all whom it may concern:

Be it known that I, Billy M. Stephens, a citizen of the United States, residing at Warren, in the county of Warren and State of Pennsylvania, have invented a new, original, and ornamental Design for a Lubricating Unit, of which the following is a specification, reference being had to the accompanying drawing, forming part thereof.

In the drawing:

The figure is a perspective view of a lubricating unit, showing my new design, the lubricating unit having the same appearance from both sides.

I claim:

The ornamental design for a lubricating unit, as shown and described.

In testimony whereof I affix my signature.

BILLY M. STEPHENS.
